RICHARD M. HOPKINS, OF RUTHERFORD, NEW JERSEY, ASSIGNOR TO AMERICAN DISTRICT TELEGRAPH COMPANY, OF NEW YORK, N. Y., A CORPORATION OF NEW JERSEY.

SUPERVISORY SIGNALING SYSTEM.

1,395,826.

Specification of Letters Patent.

Patented Nov. 1, 1921.

Application filed March 18, 1918. Serial No. 223,146.

To all whom it may concern:

Be it known that I, RICHARD M. HOPKINS, a citizen of the United States, and a resident of Rutherford, county of Bergen, and 5 State of New Jersey, have invented certain new and useful Improvements in Supervisory Signaling Systems, of which the following is a specification, reference being had to the accompanying drawing, which forms a part 10 hereof.

This invention relates to supervisory signaling systems especially applicable to sprinkler or other water supply installations designed as a protection against fire, and 15 more particularly to electric signaling systems for such installations. The invention is also applicable to the fire exits of a building to show at all times whether such exits are in proper working condition; it is also 20 applicable to the doors, windows, etc., of a building to show their condition as a protection against burglary. It may also be applied to other elements whose condition it may be desirable to supervise. The system 25 is especially, though not exclusively, adapted to be applied locally in a building or buildings existing as a separate local unit. Its general purpose, as a whole, is to provide an efficient arrangement whereby any change in 30 the service condition of the sprinkler or other water supply installation, or of the doors and windows, etc., of a building or other elements to be supervised, will be locally signaled to a central station, such as 35 the office of the local supervisor or person in charge, and whereby the particular locality in the installation or building where such change has occurred will be indicated, with the result that the installation or other 40 elements to be supervised may be kept at all times in a high state of efficiency.

In the accompanying drawing forming part of this specification, the system is shown in normal condition in diagram, and in its preferred form as applied to a sprinkler installation.

Referring now to the particular arrangement as shown in the drawing, 1 and 2 are main circuit wires leading from any convenient source of electric current. Connecting 50 with these main wires are one or more branch circuits or loops extending to various parts of the sprinkler installation. In the

drawing, four of such branch circuits or loops are shown. The upper one bearing the legend Gate valve loop extends to the various gate valves of the sprinkler installation, the location of the gate valves being indicated by crosses on the circuit loop. The next circuit loop extends to devices in the installation responsive to variations of the water pressure and bears the legend Pressure loop. The location of these pressure devices is also indicated by crosses on the circuit loop. The next circuit loop extends to devices in the installation associated with the various tank floats and bears the legend Tank float loop. The locations of these devices are also indicated by crosses on the circuit loop. The lower circuit loop extends 70 to the various devices of the installation responsive to the water flow and bears the legend Water flow loop. The locations of these devices are indicated by the contacts connected with the loop. 75

3 is a signal, preferably an audible signal, such as a bell, connected in the local circuit with a battery 4, such circuit being indicated by the wires 5 and 6. The wire 5 is connected with a contact 7 movable between contacts 8 and 9. Wire 6 is connected with a switch 10 resting normally on the contact 11 and adapted to be moved over to contact 12. The switching device consisting of the contacts 7, 8 and 9, is controlled by an electro- 80 magnet 13 in the circuit of the gate valve loop. For this purpose, its armature 14 carries an arm 15 which actuates the contact 7. When the magnet 13 is energized to draw up its armature 14, the arm 15 moves 85 to the left and permits the contact 7 to rise to make connection with the contact 9. This is the position of the parts shown in the drawing. When the magnet 13 is deenergized, its armature 14 moves to the left and 90 the arm 15 moves to the right, thereby throwing contact 7 into connection with contact 8. Armature 14 carries a visual signal 16 and the magnet and associated switching device are preferably inclosed within a box having 100 an opening 17 through which the signal 16 is visible when magnet 13 is deenergized. 95

19 is one of the gate valves of the sprinkler installation. Associated with it is a pair of contacts 20 and 21. When the gate valve is 105 opened and its stem elevated, contacts 20 and

- 21 are closed, as shown in the drawing. When the gate valve is closed and its stem lowered, contacts 20 and 21 are thereby opened. In the preferable arrangement, as shown in the drawing, the gate valve loop is normally closed and the gate valves are all open to permit a free flow of water. The other gate valves and their contacts are the same as that just described.
- 10 Instead of employing the contacts 20 and 21 to effect a break in the gate valve loop and thereby deenergize magnet 13, as might be done, it is preferable to throw in an added resistance when these contacts are opened and thereby deenergize magnet 13, employing this added resistance being in the form of a coil for an electromagnet to operate a local signal to indicate the position of the gate valve. This arrangement is shown in
- 15 the drawing, the added resistance being in the form of an electromagnet 22 connected in multiple with the contacts 20 and 21. When these contacts are opened, magnet 22 is energized and its armature 23 is drawn up, thereby lowering the target 24 to obscure the disk 25. The target 24 is ordinarily colored red and the disk 25 is ordinarily white. When the gate valve 19 is open, therefore, the white disk 25 will be displayed to indicate this fact. When the gate valve is closed, the target 24 will be lowered to indicate that the gate valve is closed. There are preferably similar electromagnetic and signaling devices associated with each gate
- 20 valve.
- When a gate valve, such as 19, is closed, its contacts 20 and 21 will be opened to include in the circuit the magnet 22 whose added resistance to the circuit deenergizes magnet 13, thereby displaying signal 16 at opening 17 and closing contacts 7 and 8. This closes the circuit of signal 3, normally open, at contacts 7 and 8, and causes the signal 3 to indicate danger or give a call indication as by ringing a bell. This draws the supervisor's attention and by signal 16 he is able to observe that the signal has been transmitted from the gate valve loop which is thereupon inspected to determine the location of the particular gate valve from which the signal has been transmitted. The target 24, or other signal associated with the gate valve, having dropped, facilitates the inspection of the gate valves.
- 25 As soon as the supervisor issues the order to inspect the gate valves, he throws the switch 10 over to the right, thereby disconnecting the wire 6 from contact 11 and connecting it with contact 12. This breaks the circuit of signal 3 and its danger or call indication ceases. Contact 12 is connected by wire 26 with contact 9. Hence, when the particular gate valve from which the signal has been transmitted has been opened to again energize magnet 13 and close contacts 7 and 9,

the circuit of signal 3 is thereby again closed and signal 3 gives a second call indication to inform the supervisor that the gate valve has been opened and that the gate valve loop and signal 16 have been restored to normal condition. Thereupon he returns the switch 10 to its normal position making connection with contact 11, cutting out signal 3 and restoring everything to normal. It will be observed that switch 10 acts to cut in and cut out certain of the contacts of switching devices 7, 8 and 9 to thereby control the call indication of signal 3 or such other signaling means as may be employed in lieu thereof.

Associated with the pressure loop is an electro-magnet 27 which controls signal 28 and switching device 29 similar to the magnet 13 and its associated devices. The switching device 29 is connected with wires 85 5 and 6 in the same way as contacts 7, 8, 9 and is associated with a hand switch 30 similar to switch 10. The pressure loop is also provided at each pressure device with devices similar to that associated with gate 90 valve 19. The tank float loop is provided with similar devices.

In the preferred arrangement, as shown, the supervisory circuits are normally closed. This has the advantage that any failure of 95 current in these circuit loops or break in a circuit wire or connection will cause an alarm indication at the supervisor's office, as by signals 3 and 16.

In the water flow loop, instead of employing normally closed contacts, such as 20, 21, normally open contacts, such as 31 and 32, are used. Contact 31 is connected by a wire to one end of a magnet coil 33, whose other end is connected with one side of the circuit 105 loop. Contact 32 is connected with the other side of the water flow loop. By this arrangement, when contacts 31 and 32 are closed, a bridge across the two sides of the circuit loop is closed to shunt out magnet 34. 110 Magnet 33 is included in this branch and when the bridge is closed it is energized to display a signal in a manner similar to that of magnet 22. In other respects this circuit loop and its associated devices are the same 115 as has already been described with respect to the gate valve loop.

Contacts, such as 20 and 21, and contacts, such as 31 and 32, may be termed signal transmitting devices because of their function in transmitting signals to the supervisor's office.

What I claim is:

1. In a supervisory signaling system, the combination of a signal and a circuit therefor; a normally closed supervisory circuit including an electroresponsive device provided with switching contacts having a normal position and a position of change, a manually controlled switch and connections 120

between the switch and said contacts where-
by the latter may be cut into and out of the
signal circuit in both said positions, a cir-
cuit closer in said supervisory circuit and a
5 supervised device controlling said circuit
closer.

2. A supervisory signaling system as set

forth in claim 1, and an electro-responsive
indicating device in shunt to said circuit
closer.

10 This specification signed this 15th day of
March, A. D. 1918.

RICHARD M. HOPKINS.
